UNITED STATES PATENT OFFICE.

ELMER C. COREY, OF NORWOOD, OHIO.

FORCER STEAM VALVE.

Application filed May 19, 1920. Serial No. 382,501.

To all whom it may concern:

Be it known that I, ELMER O. COREY, a citizen of the United States, and residing at Norwood, in the county of Hamilton and State of Ohio, have invented a new and useful Improvement in Forcer Steam Valves, of which the following specification is a full disclosure.

This invention relates to a means for maintaining a certain spaced relation between an injector operating handle and the steam inlet pipe of the injector, the provision of such means being necessitated by the wearing or grinding of the valve 15 operated by the said handle.

An object of the invention is to accomplish the above result by the use of a split, cylindrical cup-shaped coupling ring in which the valve stem is loosely held, and to so form the said coupling that its position within the valve may be reversed in a simple manner to compensate for the wear of the valve seat.

Other objects and certain advantages will appear in the description following, and special reference is made to the drawings, which form a part of this specification, in which:

Fig. 1, is a central vertical section through the steam inlet valve of one type of injector, showing my improved adjusting nut in position.

Fig. 2 is a fragmentary view, similar to Fig. 1, showing the reversed position of my improved adjusting nut,

Fig. 3 is a section on line 3, 3, Fig. 1.

Fig. 4 is a perspective view of the two halves of the nut.

The numeral 1 designates generally the main casing of a double tube injector, 2 the steam inlet passage, 3 the steam inlet port, 4 the forcer steam tube, and 5 a disk-valve for controlling the port 4. A conical valve 6, normally seated as at 6', is provided with a hinged extension 7, acting as a guide. At that side of the valve 6, opposite the extension 7, there is provided a hollow cylindrical extension or hub portion 8, interiorly threaded at 9, for the reception of a threaded plug 10, the same being provided with a central cylindrical bore 11 for the reception of the valve control stem 12 of the valve 6. The extension 8 is chambered at 13, to receive a two-piece cylindrical, cup-shaped adjusting coupling or collar 14, which pro-

vides interior annular ribs 15 and 16, defining annular recesses 17 and 18.

As shown in Fig. 1, the rib 16 engages an annular recess 19, cut adjacent the end of the stem 12, and the head 20 rests in the recess 17. This is the normal position of the adjusting coupling collar before the valve 6 and its valve seat 6' have been ground or worn. The valve stem 12 passes outwardly through a packing gland, in the casing 1, and is pivoted to the valve control lever 25, as at 26, the lower end of the lever 25 being pivoted to the extension 27, as at 28.

With the split collar 14 placed as shown in Fig. 1, and with the valve 6 in its closed position, the spaced relation of the lever handle 25^a, relative to the stem inlet pipe 2^a, is such that ample room is provided between the operator's hand, which is grasping the lever, and the steam inlet pipe 2^a. When, however, the valve and its seat have been ground, to a certain degree x , as represented by the parallel dot-and-dash lines in the drawing, the handle end 25^a of the lever 25 assumes the position shown at 25^b, by the dot-and-dash lines, and in such position the hand of the operator strikes the steam inlet tube 2^a.

To overcome the above difficulty, the position of the collar 14 is reversed, as shown in Fig. 2, the rib 15 engages the recess 19, the stem 12 is adjusted outwardly, and the spaced relation of the lever handle 25^a restored, thus giving the desired hand room between said handle and inlet pipe 2^a.

The divided collar may be said to have a mortised connection with the end of the stem and is arranged to permit the collar to be transposed for extensibly connecting the stem within the valve. The collar, may if desired, be rigidly clamped within the socket of the valve between the end of the nut 10 and the shoulder of the valve bore as an annular end wall of the chamber or socket 13. The mortise connection between the divided collar and stem head may be proportioned to allow a slight longitudinal play between the connected parts for self adjustment of the valve to the seat.

The ports for the valves 5 and 6 are respectively aligned and provide two relatively fixed seats for the valves. The stem 30 of the valve 5 has a head 31 engaged within the bore of the valve 6 and confined between the shoulder 33 and plug screw 34.

threaded into the bore, the connection permitting a slight longitudinal movement of the stem within the valve 6, allowing the valve 5 to seat independently of the valve 6. 5 The plug screw 34 is threaded into the bore of the valve 6 and bears against a shoulder at the end of the thread as a seat, for securely sealing the bore against leakage or escape of fluid through the bore from the opposite 10 sides of the valve.

Having described my invention, I claim:

1. A valve having a cylindrical hub extending from one side thereof, a valve stem provided with an annularly grooved end engaged into the hub of said valve, a divided collar having a plurality of internal annular ribs adapted to be alternately engaged into the groove of said stem for extensibly connecting the stem to the valve, and a nut 15 engaged about the valve stem and threaded into said valve hub for confining the divided collar within the valve hub and thereby removably connecting the stem to the valve.

2. A valve having a cylindrical hub extending from one side thereof, a valve stem provided with a headed end engaged into the hub of said valve, a divided collar having means cooperating with the headed end of said stem for extensibly connecting the 20 stem to the valve, and a nut engaged with said valve hub for confining the divided collar within the valve hub and removably connecting the stem to the valve.

3. A valve having a central socket in one 25 side thereof, a valve stem having an end engaged in said socket, a divided collar cooperatively engaged about said stem within the

socket, and adapted to be set to transposed positions for extensibly connecting the stem to the valve, and means for confining the divided collar within the valve socket. 40

4. A valve having a central socket into one side thereof, a valve stem having an annularly grooved end engaged into said socket, a divided collar engaged over the 45 end of said stem and cooperatively with the annular groove thereof, said collar being adapted to be set to transposed position for extensibly connecting the stem to the valve, and a nut concentric with the stem threaded 50 into said socket for removably confining the divided collar within the valve socket.

5. In a compound valve for seating over two relatively aligned and fixed ports, a first valve centrally bored to provide sockets for 55 the ends of the stems projecting from opposite sides of said valve, a valve stem having an end engaged into said valve bore from one side of the valves, a divided collar cooperatively engaging about said stem within 60 said bore for extensibly connecting the stem to the valve, a nut threaded into said valve bore for confining the divided collar within the valve socket, and a second valve having a stem engaged and confined within 65 the bore of said first valve from a side opposite to said first-named stem.

In witness whereof, I hereunto subscribe my name, as attested by the two subscribing witnesses.

ELMER O. COREY.
